ATTORNEY

UNITED STATES PATENT OFFICE.

CLARENCE W. BENNETT, OF NEW YORK, N. Y.

VELOCIPED.

1,422,171.

Specification of Letters Patent. Patented July 11, 1922.

Application filed January 22, 1920. Serial No. 353,262.

To all whom it may concern:

Be it known that I, CLARENCE W. BENNETT, a citizen of the United States, residing at New York city, county Bronx, State of New York, have invented certain new and useful Improvements in Velocipedes, of which the following is a specification.

This invention relates particularly to the seat construction for toy velocipedes, the objects of the invention being to provide a relatively simple and inexpensive construction of this character and which will be strong and well braced and capable of withstanding the hard usage to which such parts are usually subjected.

The invention involves a number of novel features of construction, combination and arrangement of parts, all of which will be set forth in detail in the following specification, reference being had for the purpose of this disclosure to the drawing accompanying and forming a part hereof.

In the drawing referred to Figure 1 is a perspective view of a child's velocipede having an adjustable seat construction embodying the features of this invention.

Figure 2 is a broken plan view of a portion of the frame, the seat supporting bracket and the seat post, the seat or saddle not being shown.

Figure 3 is a broken side elevation of these several parts.

In the construction illustrated, the frame of the vehicle is made up of two side members 5 and 6 which are secured together by suitable fastenings 7, said frame carrying the sleeve 8 at its forward upper end, in which the steering post is journaled and being attached at its rearward and lower end to the rear axle 9.

The seat or saddle 10 is supported by a bracket 11 which, as shown particularly in Figure 2, may be made of a strap of sheet metal doubled on itself to provide a loop portion 12 and having the end portions 13 thereof brought together in flat engagement and secured between the side members 5 and 6 of the frame by the rivets or other suitable fastenings 14.

As shown most clearly in Figure 3, the loop portion of this bracket projects rearwardly from the frame and overstands a portion of the frame which is curved downwardly at that point. This projecting and overstanding portion of the bracket is braced and supported, in my invention, by giving

it a bearing at the point where it emerges or projects from the frame. Thus, in the illustration, I have shown the bracket at the points where it is expanded or widened out to form the loop as bearing on the upper edge of the frame, as indicated at 15. These bearing points 15 on the side members of the frame, in conjunction with the fastenings 14, firmly support the bracket and brace the same in such a way as to prevent collapse of the bracket.

The seat post is illustrated as of forked construction having the spaced side members 16 and 17 which pass down through the loop in the bracket and are adjustably held therein by a securing plate 18, which clamps the post edgewise against the rear end of the loop by means of a clamping bolt 19 and nut 20. This seat post is braced and guided at its lower end by having the side members 16 and 17 thereof straddle the side members of the frame. The frame thus provides bearings for the side members of the seat post so that any twisting effort exerted on the seat is opposed by the engagement of the lower ends of such side members directly with the frame. This provides a simple, relatively light and at the same time comparatively strong construction, which is capable of withstanding both unusual as well as the usual strains to which such parts might be subjected.

With the construction disclosed, it will be seen that the seat parts are braced both vertically and laterally and this without adding any weight, and in fact, using relatively light and inexpensive material. It will also be clear that the bracing of the parts in the manner described does not interfere with the easy adjustment of the seat post.

What I claim is:

1. In a velocipede, a frame having side members, a seat post bracket having parts held between said side members and a part projecting beyond said side members, said bracket at the point where it projects from the side members having its lower edges bearing directly on the upper edges of such side members, and a seat post adjustably held in the projecting portion of the bracket.
2. In a velocipede, a frame having side members, a seat post bracket having parts held between said side members and a part projecting beyond said side members, said bracket at the point where it projects from

the side members having its lower edges bearing on the upper edges of such side members, and a seat post adjustably held in the projecting portion of the bracket, said seat post having spaced side members straddling the side members of the frame.

3. In a velocipede, a frame, a seat post bracket having a portion secured to said frame and a portion projecting beyond the frame, said bracket at the point where it projects from the frame having its lower edges bearing directly on the upper edges of such frame, and a seat post adjustably held in the projecting portion of the bracket.

4. In a velocipede, a frame, a seat post bracket having a portion secured to said frame and a portion projecting beyond the frame, said bracket at the point where it projects from the frame having its lower edges bearing on the upper edges of such frame, and a seat post adjustably held in the projecting portion of the bracket, said seat post having dependent portions arranged to bear on a part of the frame below the projecting portion of the bracket.

5. In a velocipede, a frame, a seat post

bracket having a portion secured to said frame and a portion projecting beyond the frame, said bracket at the point where it projects from the frame having its lower edges bearing on the upper edges of such frame, and a seat post adjustably held in the projecting portion of the bracket, said seat post having dependent spaced side members straddling a part of the frame below the projecting portion of the bracket.

6. In a velocipede, a frame comprising side members, a seat post bracket consisting of a strap having portions brought together and secured between said side members of the frame and having a rearwardly extending portion widened out into a loop, said loop having bearings at its lower edge on the upper edges of the side members of the frame and a seat post adjustably secured in the loop portion of said bracket.

In testimony whereof I have affixed my signature in presence of two witnesses.

CLARENCE W. BENNETT.

Witnesses:

JOHN M. QUIGLEY,
ELMER C. RYLANDS.
